UNITED STATES PATENT OFFICE.

SYDNEY E. MATTHEWS, OF VICTORIA, BRITISH COLUMBIA, CANADA.

MUSIC-LEAF TURNER.

1,165,431.

Specification of Letters Patent. Patented Dec. 28, 1915.

Application filed March 27, 1915. Serial No. 17,574.

To all whom it may concern:

Be it known that I, SYDNEY E. MATTHEWS, a subject of the King of Great Britain, residing at Victoria, in the Province of British Columbia and Dominion of Canada, have invented new and useful Improvements in Music-Leaf Turners, of which the following is a specification.

The invention relates to a music leaf 10 turner, and has for its primary object to provide a device of this character wherein the leaves of sheet music will be successively turned without necessitating the fingering of each sheet of music for this purpose.

Another object of the invention is the provision of a device of this character wherein the construction thereof is of novel form so as to permit its use on the music rests of pianos, organs or the like, or upon music 20 stands or racks to automatically turn the respective leaves of music when placed thereon.

A further object of the invention is the provision of a music leaf turner wherein the leaves of the music can be turned back after 25 the automatic action of the device, thus enabling the quick and easy handling of the music while the musical instrument is being played.

A still further object of the invention is 30 the provision of a device of this character which is simple in construction, reliable and efficient in operation, strong, durable, and inexpensive in manufacture.

With these and other objects in view, the 35 invention consists in the construction, combination and arrangement of parts as will be hereinafter fully described, illustrated in the accompanying drawings, and pointed out in the claim hereunto appended.

In the drawings:—Figure 1 is a front elevation of a music leaf turner constructed in accordance with the invention. Fig. 2 is a vertical sectional view through a piano showing 40 the music leaf turner in edge elevation applied. Fig. 3 is a top plan view with the top portion of the bracket broken away. Fig. 4 is a vertical transverse sectional view. Fig. 5 is a fragmentary perspective view of one of the turning arms. Fig. 6 is a sectional view on the line 6—6 of Fig. 1.

Similar reference characters indicate corresponding parts throughout the several views in the drawings.

Referring to the drawing in detail, the 55 music leaf turner comprises a hanger A which constitutes the frame and includes a

shank or column 5 and a cross head 6 which is in the form of a channeled rail having threaded therein set screws 7 so that the rail can be hung upon the front upper panel or 60 section of a piano, organ or the like or upon a rack or stand for supporting music, and fastened thereto. On the end opposite the head 6 is a right angular bearing 8, while mounted upon the shank or stem 5 at spaced 65 intervals are bearings 9, and in these bearings 8 and 9 is journaled a slideable operating shaft 10 which controls the locking mechanism for the music leaf turning arms hereinafter fully described.

Mounted upon the shank or column 5 near the head 6 thereof is a bracket 11 through which is passed the shaft 10, and within this bracket are positioned a plurality of disks or wheels 12 in which are fixed the music 75 leaf turning arms 13, the wheels or disks 12 being journaled upon a stud axle 14 mounted in the bracket 11, and each wheel or disk at its periphery is provided with a stop 15 with which engages a ratchet dog 16, these dogs 80 being swingingly supported upon a pivot 17 common thereto and mounted in the said bracket 11 so as to lock the wheels or disks against rotation when engaged therewith.

The dogs 16 are formed with extensions 85 18 to which are connected coiled retractile springs 19, the same being also connected to the music leaf turning arms 13 and are trained about the peripheries of the disks or wheels 12 so that on the releasing of the 90 dogs 16 the arms 13 will be swung in one direction under the tension of the springs 19 for the turning of the leaves of the sheet music, the dogs 16 being released in a manner presently described.

Formed on the shaft 10 is a cam projection 20 which is adapted to act upon the respective extensions 18 of the dogs 16 for releasing the same from locked engagement with the disks or wheels 12 so as to release 100 the music leaf turning arms 13 for the turning of the leaves of the music. The disks or wheels 12 are formed in their peripheries with notches 21, while formed on the shaft 10 is a lug 22 so that the shaft 10 is limited 105 in its downward movement until the notches 21 register with the lug 22, thereby permitting the passing of the arm from one wheel or disk to the other when the shaft 10 is lowered in its bearings.

Suitably hinged to the bearing 8 beneath the same is an operating key or wing 23,

while formed at the lower end of the shaft 10 is a right angular extension 24 which is provided with a hook end 25 loosely engaging in an eye 26 formed on the under face of the key or wing so that on depressing the latter the shaft 10 will become lowered in the bearings 8 and 9 for bringing the cam projection 20 into engagement with the locking dogs 16 to release the disks 12 or wheels 12 for the turning of the arms 13, the latter being provided with snap fasteners or clips 27 for the detachable engagement of the leaves therein of the sheet music, and in this manner the leaves or sheets of the music are fastened to the music leaf turning arms.

Normally the arms 13 are locked by the dogs 16 at the right hand side of the bracket 15, and the notches 21 therein are disposed 20 diametrically opposite with relation to the cam projection 20 on the shaft 10. Now on depressing the key or wing 23 the shaft 10 becomes lowered, bringing the cam projection 20 into engagement with the uppermost dog 16, thereby releasing the uppermost disk or wheel 12 so that the first arm 13 to be turned will be released for the swinging or turning of the first sheet or leaf of the music. The notch 21 in the uppermost disk or wheel 12 has been brought 30 into registration with the lug 22 on the shaft 10 so that on the next depression of the wing or key 23 the shaft 10 can become lowered a sufficient distance to engage the next dog 16 for the release thereof from engagement with the next disk or wheel 12 so that the second arm 13 can be turned. This action is repeated until all of the arms 13 have been turned. Should at any time it be 40 necessary to turn back a leaf or sheet of the music, the same can be readily accomplished by the swinging of any one of the arms from left to right, the springs 19 being designed to automatically shift the

arms 13 from right to left when released 45 by the dogs 16 on manipulating the key or wing 23 hereinbefore set forth.

Surrounding the shaft 10 is a coiled spring 28, one end of which is fixed to one of the bearings and the other end fixed 50 to the shaft, and this spring is designed to act upon the latter to raise the same to normal position after the key or wing 23 has been depressed. Located in the bracket 11 is a stop pin 29 which limits the swinging 55 movement of the arms 13 when moved from right to left.

From the foregoing description, taken in connection with the accompanying drawings, the construction and manner of operation of the device will be clearly understood, and therefore a more extended explanation has been omitted.

What is claimed is:—

A music leaf turner comprising a hanger 65 having a column, a bracket fixed on the column, an operating key mounted for swinging movement at the lower end of the column, a plurality of wheels journaled in the bracket, music leaf turning arms fixed 70 in said wheels, means for moving the wheels in one direction, means for locking the wheels against rotation by the means for moving the same, bearings on said column, a shaft slidably fitted in said bearings and 75 passed through the bracket, a cam projection on said shaft to engage the locking means for releasing the same on movement of the shaft, a connection between the shaft and said key, means for fastening the hanger 80 to a support, and clips carried by the respective arms.

In testimony whereof I affix my signature in presence of two witnesses.

SYDNEY E. MATTHEWS.
